UNITED STATES PATENT OFFICE.

JOSEPH KALAS, JOSEPH KLASNA, AND FRANK BARABAS, OF CHICAGO, ILLINOIS.

VENTILATED MATTRESS.

932,024.

Specification of Letters Patent. Patented Aug. 24, 1909.

Application filed July 6, 1908. Serial No. 422,188.

To all whom it may concern:

Be it known that we, JOSEPH KALAS, JOSEPH KLASNA, and FRANK BARABAS, residents of Chicago, in the county of Cook and State of Illinois, subjects of the Emperor of Austria-Hungary, have invented certain new and useful Improvements in Ventilated Mattresses; and we do hereby declare that the following description of our 10 said invention, taken in connection with the accompanying sheets of drawings, forms a full, clear, and exact specification, which will enable others skilled in the art to which it appertains to make and use the same.

15 This invention has general reference to sanitary mattresses; and it consists, essentially, in the novel and peculiar combination of parts and details of construction as hereinafter first fully set forth and described, and then pointed out in the claims.

20 In the drawings already referred to, which serve to illustrate this invention more fully, Figure 1 is a perspective view of a bedstead provided with our improved sanitary mattress. Fig. 2 is a similar view of the mattress detached. Fig. 3 is a plan of the same, parts being shown broken to disclose underlying construction. Fig. 4 is a side-view of the mattress-frame. Fig. 5 is a 25 similar view of the mattress completed, the ventilating openings being omitted. Fig. 6 is a sectional view of a portion of the mattress, in line $\alpha\alpha$ of Fig. 3, the springs in the mattress being omitted. Fig. 7 is a 30 similar view of the bed-cloth showing the rubber hose connection with the same.

Like parts are designated by corresponding symbols of reference in all the figures.

The object of this invention is the production of an efficient and durable sanitary mattress. To attain this end we construct this mattress of a wooden, rectangular frame A, Figs. 3, 4, and 5, of proper width and length to fit a single or double bed, as the case may be, said frame being of a suitable height and having in its four corners diagonal braces B to stiffen the structure and in its center a cross-bar or slat C to prevent spreading of the sides of said frame. In the 45 outer surfaces of the sides and ends of this frame there is a groove D, Figs. 4 and 6, the object of which will hereinafter more fully appear.

E is a series of webbing secured to the 50 top and bottom edges of the ends of the

frame A, and E' a similar series of webbing secured to the upper and lower edges of the sides of said frame and crossing the longitudinal webbing E at regular intervals. At these crossings of the webbing there are 55 placed double-helical springs F, properly secured to the webbing in any desired manner. The covering for this frame consists of an inner sheet of a strong textile fabric G, such as canvas, ducking, &c., and an outer sheet 60 H of any desirable material, cotton, linen, or rubber cloth being among the desirable fabrics that may be used. Interposed between these sheets there is a layer of batting, or other suitable material I, which may be 65 sewed to the outer and inner sheets, and this covering is secured to the frame A by forcing the edges of the inner and outer sheets into the grooves D in the frame A and fastening them therein by tacks, after 70 which a tape J, is placed over the adjoining edges of said covers, to finish off the structure, said tape being secured to the frame by means of upholstery-nails K having 75 comparatively large heads as shown in the 80 various figures.

L is a series of gromets passed through the outer and inner layers and the filling of the covering of the frame A and retained by washers N, Fig. 6, thereby securely uniting the covering and at the same time providing passages or ducts P for the escape of air from the interior of the mattress, said gromets L being comparatively large in 85 diameter so as to afford an ample passage 90 for the air.

It will be observed that this mattress as described is reversible, that is to say, either side thereof may be placed uppermost into the bedstead Q.

95 For the use of infants, invalids and other persons, we provide this mattress with an auxiliary sheet, R, which is preferably removably secured to the covering H, by means of buttons S, Fig. 1, so that it may be removed and replaced when desired. This auxiliary covering has centrally a hose-nipple T, Figs. 1 and 7 to which a hose or rubber tube V, is attached. The object of this auxiliary sheet, for which we prefer rubber cloth or oil-cloth, or other fabric impervious to liquids, is to provide for means to conduct urine from the bed to a receptacle V, Fig. 1, whenever the mattress is used by 100 infants and other persons requiring such 105 110

services, said hose being passed through one of the passages P in the gromets L, in an obvious manner.

We will here call attention to the fact that 5 the compound covering for the frame A not only reaches across the top and bottom surfaces thereof, but also covers the sides and ends of the said frame, thereby forming a cushion which is elastic all around, thus preventing 10 the limbs and body of patients using this mattress from coming in contact with any hard surfaces or corners thereon.

It will now be observed that by the construction heretofore described we have produced 15 a very serviceable and sanitary mattress that will be capable of being used in infants', invalids', and sick-beds, in hospitals, &c., and that can be manufactured and sold at a reasonable cost.

20 Having thus fully described our invention, we claim as new and desire to secure to us by Letters Patent of the United States—

1. A mattress, comprising in combination a rectangular frame having diagonal corner 25 braces and an intermediate transverse cross-brace, and having a continuous longitudinal groove formed entirely around its outer sides, a plurality of interwoven longitudinal and transverse fabric bands secured to the 30 sides and ends of said frame at the top and bottom thereof, a series of springs secured between said upper and lower interwoven bands at their intersections, coverings for said frame comprising a sheet of fabric secured to said frame at its top and bottom 35 sides and lying against said interwoven bands, batting laid on each of said sheets, and outer sheets laid on each layer of batting the edges of said sheets being crimped into 40 and secured in said continuous groove, a series of gromets in each of said coverings, the gromets in the upper covering registering vertically with the gromets in the lower covering, and a flexible beading bound over said groove to retain the edges of said sheets thereon.

ing vertically with the gromets in the lower covering, a supplemental removable sheet adapted to button along the sides of the 45 mattress and having an aperture adapted to register with one of said gromets and a conduit coupled to said supplemental sheet at said aperture and projected through registering gromets.

2. A mattress, comprising in combination a rectangular frame having diagonal corner braces and an intermediate transverse cross-brace, and having a continuous longitudinal groove formed entirely around its outer 50 sides, a plurality of interwoven longitudinal and transverse fabric bands secured to the sides and ends of said frame at the top and bottom thereof, a series of springs secured between said upper and lower interwoven 55 bands at their intersections, coverings for said frame comprising a sheet of fabric secured to said frame at its top and bottom sides and lying against said interwoven bands, batting laid on each of said sheets, 60 and outer sheets laid on each layer of batting the edges of said sheets being crimped into and secured in said continuous groove, a series of gromets in each of said coverings, the gromets in the upper covering registering vertically with the gromets in the lower 65 covering, and a flexible beading bound over said groove to retain the edges of said sheets thereon.

In testimony that we claim the foregoing 70 as our invention we have hereto set our hands in the presence of two subscribing witnesses.

JOSEPH KALAS.
JOSEPH KLASNA.
FRANK BARABAS.
